RAFTER MARKING APPARATUS

Robert L. Greve, Pasadena, Calif., assignor of
one-half to Norman A. Greve, Wilmar, Calif.

Application August 25, 1931, Serial No. 559,213

4 Claims. (Cl. 33—91)

My invention relates to rafter marking apparatus and it has among its salient objects to provide a simple, compact and practical rafter marking device which combines a plurality of marking edges, adjustably interconnected so that the adjustment of one member for marking one cut to be made automatically moves or adjusts another member for marking another cut in connection with said first cut, said parts or members being so connected that the proportional movements are made without any calculations on the part of the user of the instrument; to provide an instrument in which four different marking members are provided and interconnected together for automatic and simultaneous movement for marking the several cuts to be made in cutting common, hip, jack and valley rafters; to provide in an instrument of the character referred to a single scale for the guidance of the user in adjusting the instrument for the particular pitch of the roof to be constructed; and to provide an instrument of the character referred to which can be folded into small compass.

In order to explain my invention, I have illustrated one practical embodiment thereof on the accompanying sheet of drawings, which I will now describe.

Figure 1 is a top plan view of an instrument embodying my invention;

Figure 2 is a front side elevation of said instrument;

Figure 3 is a back or under side elevation thereof;

Figure 4 is an edge view as seen from the line 4—4, Fig. 3; and

Figure 5 is a cross sectional detail on the line 5—5 of Fig. 2.

Referring in detail to the drawing, my instrument as here embodied for explanatory purposes includes a body plate or member 6, having a right angle flange 7 along one side thereof, and having its opposite side cut away to different angles, as at 8 and 9, to give clearance for the members movably connected therewith. Pivotally mounted on one side of said body is a segmental marking member 10, pivoted at 11, and having a curved slot 12 therein, with thumb screw and nut at 13, for holding said marking member in different positions of adjustment. Said body is provided on its face with graduations 14, cooperating with said marking member 10, at 10', for determining the position or place for said marking member 10 for different pitches. In said body 6, concentric with the pivot 11, is a curved slot 15, through which said marking mem-

ber is connected by means of a rivet 16, with a link 17, on the back of said body, and again referred to.

Said marking member is also provided along its straight side with a parallel slot 18, and a strip or reinforcing portion 19, upon which is slidably mounted an angle member 20, having slots 20' and 20'', at right angles to each other, whereby said angle member can be adjustably and reversably mounted and held in place on said marking member 10 by means of screw and nut at 21.

On the opposite face of said body plate 6, Fig. 2, is pivotally connected another marking member 22, pivoted at 23, to said body plate, and at its end provided with a short curved slot 24, with pivot pin 25 therein, and extended through a curved slot 26 in said body plate 6, and connecting with a link 27, on the back side of said body plate, as seen in Fig. 3. Said marking member 22 is also provided with a slideable square or angle member 22', which is similar to the angle member 20, on the member 10, said angle member 22' being adjustably and reversably held in place by means of a screw 22a. These angle members are used for marking for the seat cuts for common and jack rafters.

Slidably mounted on the top side of the flange 7, on said body plate 6, is a slide plate or member 29, having an upturned part 29' to which the links 17 and 27 are connected, as seen in Fig. 3. Said slide member 29 is provided with two straight slots, as 29a, 29a, and is slidably held in place by means of rivets 30. On said side member 29 are two upstanding pins or studs, as 31 and 32, working in two curved slots 33 and 34, in two segmental marking members 35 and 36, pivoted near their pointed ends, as at 37 and 38, to the flange member 7. This makes it possible to extend the small ends of said members 35 and 36, as at 35' and 36' to give longer marking edges. A cover plate, as 39, may be placed over the operating links 17 and 27, and the upturned part 29', on the body member of plate 6. Said cover plate may be formed by bending the upper portion of plate 6 upon itself, as at 7'. This body plate 6 has bent up therefrom at right angles two lips 6', 6'', for use in placing the opposite side of the instrument against the timber as may be done to reverse the markings.

Thus I have provided a compact and practical rafter marking instrument which can be used for marking all regular pitched and gable roofs, and the four different marking members 10, 22, 35 and 36, are operatively connected together so

50

55

that they are simultaneously adjusted as the main marking member 10 is moved according to the graduations at 14, Fig. 2. The marking member 10 is used for marking the cuts for common and jack rafters. The adjustable angle or square member 20 thereon makes it possible to mark the seat cut for said rafters, as those versed in the art will readily understand. The marking member 22 is used for marking the cuts for hip and valley rafters, and the square 22' thereon makes it possible to mark the seat cut for such rafters. The marking member 36 is used for marking the side cut for the jack rafter, and the marking member 35 is used for marking the side cut for the hip and valley rafters. The marking members 10 and 22 are used for marking the plumb cuts for the rafters mentioned. The parts are so interconnected that they can be adjusted for the desired markings without special calculations and locked in position by the thumb screw 13, and the instrument can then be turned and applied in different ways to the timber T to be marked for cutting, all as will be readily recognized by those who are versed in the art.

While I have shown and described in detail one practical embodiment of my invention, I am aware that changes can be made in the details of construction and arrangement without departing from the spirit thereof, and I do not, therefore, limit the invention to the showing made for descriptive purposes, except as I may be limited by the hereto appended claims.

I claim:

- 35 1. A rafter marking apparatus including a body member having a fixed supporting part in a plane at right angles thereto, a plurality of marking members pivotally connected to said body member and said supporting part to move in planes at 40 right angles to each other about different centers, connecting means between said marking members and operable to move them relative to each other and to said body member in different planes, and graduation means for determining different positions of adjustments of said marking members.
- 45 2. A rafter marking apparatus including a body

having a part standing at right angles to said body, two marking members pivotally connected with said body to fold along side thereof in different locations, two other marking members pivotally connected with said part at right angles to said body, and connecting means connecting all of said marking members for simultaneous movements to different angles of adjustment, and graduation means for indicating the different positions of adjustment for said marking members.

3. A rafter marking device including in combination a body having a supporting part at right angles thereto, marking members adjustably connected with said body, marking members 15 adjustably connected with said part at right angles to said body, whereby said marking members on said body and on said part move in planes at right angles to each other, extension members adjustably connected with some of said marking 20 members for extending the marking edges thereof as desired, and connecting means between said marking members operable to simultaneously move said marking members to various angles of adjustment.

4. An instrument of the character referred to including a flat body member provided with graduations in circular form thereon, a supporting portion at right angles to said body member, a marking member pivotally mounted on said body member, and having a part cooperating with said graduations to determine different positions of adjustment and having a marking edge, two marking members pivotally connected at different places with said supporting portion and movable thereupon to different positions of adjustment and having each a marking edge, connecting members connecting all of said marking members for simultaneous movement and operating when one of said marking members is moved to move the other marking members to different angles of adjustment, and means for extending the marking edges of said marking members to give greater length.

ROBERT L. GREVE. 45
